Primary Examiner — Paula Allen Greene(74) *Attorney, Agent, or Firm* — W & C IP(57) **CLAIM**

We claim the ornamental design for a headphone, as shown and described.

DESCRIPTION

FIG. 1 is a front side perspective view of a headphone; FIG. 2 is a front elevational view of the headphone; FIG. 3 is a right side elevational view of the headphone; FIG. 4 is an enlarged partial view of the headphone taken from FIG. 1; FIG. 5 is an enlarged partial view of the headphone; FIG. 6 is an enlarged partial view of the headphone taken from FIG. 2; FIG. 7 is an enlarged partial view of the headphone taken from FIG. 3; FIG. 8 is an enlarged partial end view of the headphone taken along line 8-8 of FIG. 7; and, FIG. 9 is a reference enlarged partial end view of the headphone taken along line 8-8 of FIG. 7, wherein an earphone cord is omitted. Portions of the drawings shown in broken lines form no part of the claimed design.
